DESIGN FOR A COMBINATION CAN OPENER AND SEALER

William J. Bechtel, Akron, Ohio

Application June 13, 1940, Serial No. 92,971

Term of patent 3½ years

To all whom it may concern:

Be it known that I, William J. Bechtel, a citizen of the United States, residing at Akron, in the county of Summit and State of Ohio, have invented a new, original, and ornamental Design for a Combination Can Opener and Sealer, of which the following is a specification, reference being had to the accompanying drawing, forming part thereof.

I claim:

The ornamental design for a combination can opener and sealer, as shown.

WILLIAM J. BECHTEL.
